Mary Georgina Koerber, 706 S. Garfield,
Mason City, Iowa 50401

Filed June 26, 1969, Ser. No. 17,886

Term of patent 14 years

Int. Cl. D3—02

U.S. Cl. D87—3

FIG. 1 is a perspective view of the paper boy collection bag, embodying this invention;

FIG. 2 is a front elevation thereof; and

FIG. 3 is a side elevation thereof, partly in section and showing the pocket of the bag open.

The back of the bag is plain, except for the attachment of the straps thereto, as indicated in FIG. 1.

I claim:

The ornamental design for a paper boy collection bag, substantially as shown and described.
